J. E. ARMSTRONG.

AUTOMATIC DRAIN AND PRESSURE RELIEF VALVE.

APPLICATION FILED FEB. 4, 1919.

1,343,382.

Patented June 15, 1920.

INVENTOR:
John Edward Armstrong
Wm Wallace White, Atty.

UNITED STATES PATENT OFFICE.

JOHN EDWARD ARMSTRONG, OF NEWCASTLE-UPON-TYNE, ENGLAND.

AUTOMATIC DRAIN AND PRESSURE-RELIEF VALVE.

1,343,382.

Specification of Letters Patent. Patented June 15, 1920.

Application filed February 4, 1919. Serial No. 274,970.

To all whom it may concern:

Be it known that I, JOHN EDWARD ARMSTRONG, of 15 Wolseley Gardens, Jesmond, Newcastle-upon-Tyne, England, a subject of the King of Great Britain and Ireland, have invented certain new and useful Improvements in or Relating to Automatic Drain and Pressure-Relief Valves, of which the following is a specification.

10 This invention relates to valves for automatically draining off water of condensation and relieving pressure in engine cylinders, turbine casings and the like. The object of this invention is to provide an improved valve for this purpose.

A valve made in accordance with this invention is characterized by the fact that water of condensation is utilized to keep the valve open after steam has been admitted to the steam chest of the engine cylinder or turbine casing, or when the valve has been unseated by excess pressure in the ends of the cylinder or turbine casing, and thereby allowing the engine or turbine to make several revolutions, until the water due to condensation priming or other cause is discharged and the excess pressure released.

One form of valve made in accordance with this invention comprises a casing, a cylinder and a chamber in said casing, a port in said chamber adapted to admit steam and water of condensation formed in the engine cylinder or turbine casing, a piston working in said cylinder, said piston being provided with a spindle on which is mounted a valve adapted to close said port, said spindle passing through a gland in said cylinder at the end nearest said chamber, said gland being provided, if desired, with suitable packing or grooved to form a watertight joint. The said chamber is provided with an exhaust port open to atmosphere, said port being arranged to allow the lower end of said chamber to fill up above the level of said cylinder end with water of condensation, which water is admitted to said cylinder through ports near the end of said cylinder, which ports are adapted to be closed by the piston by steam pressure from the steam chest of the engine cylinder or turbine casing. Ports are disposed in said cylinder through which the water is forced into the chamber of the valve as the piston valve comes to the end of the stroke, whereby the valve in the piston is kept off its seat for several revolutions of the engine or turbine,

while water due to condensation, priming or other cause is discharged from the engine cylinder or turbine casing to atmosphere.

Referring to the drawings filed herewith:—

Figure 1 is a longitudinal section of one form of valve made in accordance with this invention and adapted for use in engine cylinders or turbine casings.

Fig. 2 is a longitudinal section of a valve adapted for use in draining and relieving excessive pressure where the engine cylinders or turbine casings are connected by a passage and where the ends of the cylinders or turbine casings are adapted to be opened to the atmosphere when excess pressure occurs at either end of the cylinder or turbine.

Fig. 3 is a longitudinal section of another construction.

Fig. 4 is a transverse sectional view taken approximately on the line 4—4 of Fig. 1.

Within the casing *a* is a chamber *b* which is provided with an inlet port *c* and an exhaust port *d*. At the base of the casing is a cylinder *e* which extends into the casing *a* leaving an annular space *f* between the casing and the cylinder. The top of the cylinder *e* is closed by a cover *g* and is provided with a small port *h* disposed just below the cover *g*. Ports *k* *l* lead from the annular space *f* to the cylinder *e*. A piston *m* provided with a spindle *n* works in the cylinder *e*. At the head of the spindle *n* is a valve *o* adapted to close the inlet port *c*. The spindle *n* is provided with a cavity *p* which is connected by ports *r* to the space *s* above the piston *m*. The ports *k* *l* are disposed just above the top of the piston when the piston is down and the ports *r* just below the cover *g*. The casing *a* is adapted to be connected to the engine cylinder or turbine casing by a screwed connection *t* and to the steam chest of the engine cylinder or turbine casing by the connection *v* to admit steam to the valve cylinder *e*.

In the form shown in Fig. 2 the spindle *n* is provided with two valves *o* and *w* adapted to close the ports *c* and *2* leading respectively to passages *3* and *4* from the ends of the engine cylinder or turbine casing. The operation of the valve is similar to that described with reference to Fig. 1.

A valve of the type as shown in Fig. 3 is provided with one or more ball valves controlling the ports *k* leading from the

chamber *c* to the cylinder *e*. The object of these ball valves is to admit the water of condensation to the cylinder *e* if and when the valve is forced off its seat by excess pressure when the engine or turbine is running, thereby keeping the valve open until the excess pressure is released and all water discharged.

In this construction the ports *k* are arranged to admit water through the ports *k* to the space above the piston *m* to the cylinder *e* immediately the valve has moved off its seat, and not after the piston valve has uncovered said ports as in the construction shown in Figs. 1 and 2. A valve of this type may be constructed with a single valve as shown in Fig. 1.

The valve must be fitted to work in a vertical position with the connection *t* or the outlets 3 and 4 uppermost to allow the valves *o* and *w* to unseat the ports *c* and 2 by gravity when steam is not admitted to the cylinder *e*. The action of the valve is as follows:—Any water condensing in the cylinder of the engine or turbine finds its way into the chamber *b* and through the ports *k* into the space *s* on top of the valve piston. Any excess of water entering the cavity *p* finds its way through the ports *r* into the space *s* on top of the valve piston. When steam is turned on a small rise of the piston *m* closes the ports *k* and *r* and the piston is prevented from rising to close the port *c* until the water in the space *s* is forced out through the miniature port *h* then permitting the engine to make several revolutions until water due to condensation priming or other cause has been discharged. After the port *c* has been closed it will be reopened should any excess of pressure be created in the cylinder of the engine or turbine casing by water of condensation, the water will then flow into the chamber *b* and thence through the port *k* to the space *s* whereupon the valve *o* is again kept open until the water in the space *s* has been forced out through the port *h*. The size or number of the ports *h* may be determined or varied to suit requirements.

The action by which the ports *k* are closed by the valves 5 is as follows:—

When steam is admitted to the engine cylinder or turbine casing, the pressure which is exerted on the water contained in the space *s* on top of the valve piston by steam pressure on the piston *m* keeps the ball 5 against the seat until the water has been forced through the port *h* and the port *c* sealed by the valve *o*.

What I claim as my invention and desire to secure by Letters Patent is:—

1. In an engine cylinder drain valve device, a normally open valve controlling the outlet of the condensation water from the

engine cylinder, a piston operatively connected to the valve and movable in a cylinder; means for admitting fluid pressure to the piston to close the valve on steam being admitted to start the engine, and means for causing some of the condensation water to be trapped to prevent the closure of the said valve until the engine has made some revolutions and has expelled the condensation water to the outlet.

2. In an engine cylinder drain valve device, a normally open valve controlling the outlet of the condensation water from the engine cylinder, a piston operatively connected to the valve and movable in a cylinder, said cylinder being adapted to admit fluid pressure to the piston to operate the valve to closed position on steam being admitted to start the engine, and means carried by the valve operating parts for automatically causing condensation water to be trapped by the initial movement of the said parts to prevent the closure of the valve until after the engine has started.

3. In an engine cylinder drain valve device a valve controlling the outlet of the condensation water from the engine cylinder and adapted to be unseated by excess pressure in said cylinder, a piston operatively connected to the valve and movable in a cylinder, said cylinder being adapted to admit fluid pressure to the piston to operate the valve to closed position on steam being admitted to start the engine, and means carried by the valve operating parts for automatically causing condensation water to be trapped by the initial movement of the said parts to prevent the closure of the valve when the valve has been unseated.

4. In an engine cylinder drain valve device, a casing, a passage therein leading from the engine cylinder to a chamber for condensation water, a valve controlling the said passage, an exhaust port in the wall of the said chamber, a cylinder inclosed in the said chamber communicating at one end with the engine steam chest, a gland in the other end of the cylinder, a piston movable in the cylinder having a spindle passing steam tight through the said gland and operatively connected to the said valve, one or more ports in the cylinder wall controlled by the said piston, a cavity in the piston spindle, one or more ports leading from the cavity to the exterior of the spindle and adapted to be shut off by the said gland on the piston being moved from its inoperative position, and a restricted passage through the cylinder wall leading to the condensation water chamber.

In testimony whereof I have signed my name to this specification.

JOHN EDWARD ARMSTRONG.
